UNITED STATES PATENT OFFICE.

VICTOR BEAUREGARD, OF BIDDEFORD, MAINE, ASSIGNOR OF ONE THIRD HIS RIGHT TO HENRY I. LORD, OF SAME PLACE.

IMPROVEMENT IN MACHINERY FOR CUTTING BOOT AND SHOE HEELS.

Specification forming part of Letters Patent No. 154,826, dated September 8, 1874; application filed February 27, 1874.

To all whom it may concern:

Be it known that I, VICTOR BEAUREGARD, of Biddeford, in the county of York and State of Maine, have invented certain new and useful Improvements in Machines for Cutting Boot and Shoe Heels; and I do hereby declare that the following is a full, clear, and exact description thereof, that will enable others skilled in the art to which it appertains to make and use the same, reference being had to the accompanying drawings and to the letters of reference marked thereon, which form a part of this specification.

Figure 1 is a side elevation. Fig. 2 is an opposite side view, parts broken away. Fig. 3 is a back view. Fig. 4 is a top plan with parts broken out and away. Fig. 5 is a detail view in section. Fig. 6 is a side view of the eccentric and ring. Fig. 7 shows a detail of the delivering-arms. Fig. 8 is a detail of the delivering-arms, showing the disk for holding and releasing the nails, as required.

The purpose of my invention is to produce a machine for the cutting and preparation and arrangement of heel-lifts for attachment to a boot or shoe, and also for a method for producing the said heels composed of the successive lifts for such application.

The functions performed by the different parts of the machine are as follows: First, cutting the leather into required number of lifts to constitute a heel; second, perforating the lifts thus cut and superimposed with a single hole for the reception of a uniting-nail; third, presenting to and forcing into said perforation the said uniting-nail; fourth, throwing out from the forming-die the lifts thus cut and united.

Other subordinate auxiliary functions are performed by minor portions of the machine, but these will be specified in their order in the progress of the description of the whole operation.

The operative parts of my machine are set upon two frames—one a fixed, the other a traveling, one. A shows the fixed frame; B, the traveling one. The fixed frame has guides, *a*, in which the traveling frame moves. Connected with the fixed frame A are the main shaft *b* of the machine, the shaft *c* with its ec-

centric *d*, gears *e* and *f*, clutch *g* with its lever *h*, rod *i*, lever *j*, weighted arm *k*, catch *l*, forming-die *m*, plunger *n*, stop *o*, and standard *o'*. Upon the movable frame B are arranged the following devices: The nail-receptacle *p*, with its delivering device *q*, stop *r*, lever *s*, slide *t*, spring *u*, rod *v*, with the awl *w*, and catch *x*, catch *y*, and pressure-block *z*. Upon the main shaft *b* is rigidly set the gear *e*, matching with the gear *f*, which is rigidly attached and imparts motion to the shaft *c*. Upon this shaft is set the eccentric *d*. This eccentric, by means of the rim *a'* and jointed rod *b'*, imparts the vertical motions to the traveling frame B. This is only done, however, when the clutch *g* has been united, for the gear *e* is set upon a sleeve or is loose upon the shaft *b*, and is only rotated when the clutch *g* is united, as before described.

This clutch is operated by means of the two-armed lever *h*, rod *i*, and pivoted bifurcated lever *j*. When the clutch *g* is properly set, the motion of the main shaft *b* draws downward the traveling frame B, so that the pressure-block *z* is brought over and in contact with the cutting-edges of the die *m*, which receives the lifts as they are cut out of the leather, each successive lift pressing down the foregoing one until the cavity of the die is filled, and receiving also the perforation of the awl *w*. This awl is set upon the end of the rod *v*, which rod moves horizontally into the center of the pressure-block *z*, in order to make the perforation in the center of the lifts. This rod *v* moves in a proper guide, *c'*, and is operated by the lever *s*, which is pivoted at *d'*. When the requisite number of lifts have been cut by the die and perforated by the awl the lever *s* is drawn forward, by which movement the rod *v*, with the awl, is withdrawn from the slot in the pressure-block. This same movement of the lever *s* moves forward the rod *e'*, which enters an aperture, *f'*, in the part *g'* of the movable frame, thereby forcing downward therein a spring-plunger, *h'*. This plunger has a broad bottom, which fills the space in the bottom of the pressure-block *z*, and serves to force through the lifts in the die *m* the uniting-nail. The same movement of the lever *s* whereby the awl is withdrawn and the spring-plunger forced down turns the

nail-box p , and with it the delivering-arms q , so that by the extremities k' of said arms a nail is placed immediately over the perforation which has been made in the lifts in the forming-die m . This takes place at a time when the movable frame B is so elevated by the operations of the machine that the pressure-block z is at the farthest remove from the die m . Then, by the further operations of the machine, the movable frame commences to descend. When the movable frame has approached sufficiently near the die m to have forced the uniting-nail a portion of its length into the perforation in the lifts in the die, the delivering-arms q are turned away and out from under the descending pressure-block z , leaving the nail partially inserted into the lifts, and to be driven completely through the same when the pressure-block z has descended so as to be in contact with the die m . The means by which the above operation is accomplished are as follows: Upon the rear end of the rod v is shown the catch or shoulder y . Connected with the nail-box p is seen the vertical rod l' . Around this rod is wound the spiral spring m' . The rod is held in proper supports n' . The nail-box is so connected with the rod l' as to turn with it. Rigidly attached to the bottom of the rod l' is the curved arm p' . Now, as the rod v is thrown backward by the forward movement of the lever s , the catch y strikes the curved arm p' , thus turning the vertical rod l' , and with it the nail-box p . Thus the delivering-arms q , being connected with the nail-box, are so swung that their lower extremities k' are swing under the pressure-block z , as before described. When the downward motion of the traveling frame B begins, the curved arm p' is held on the catch or shoulder y . The descent of the frame brings the curved arm in contact with the top end of the standard o' , and is thereby thrown off from the catch y . Thereupon the spiral spring m' operates to turn the nail-box, and so swing the delivering-arms q out from under the descending pressure-block z . The bottom of the nail-box is provided with slots q' , in which the nails being placed, and the box being in an inclined position, and being somewhat agitated by the rack r' and the arm s' as the traveling frame rises and falls, they are directed into the space between the delivering-arms q . In this space they descend until they strike the spring-stop t' . When the delivering-arms are moved so that their extremities k' pass under the pressure-block, the spring-stop t' strikes the catch x . By this contact the disk u' is so rotated, by means of the curved arm v' , that the nail which rests in the recess w' is released, and allowed to slide downward in the space between the two arms until it reaches their extremities, where it is stopped. Thus as fast as the arms deliver a nail under the pressure-block z , they are supplied with another, the disk u' , by means of a spiral or other spring wound around a stock, returning to such position that the recess w'

is prepared to receive another nail. When the lever s is thrown forward, as before described, it moves the slide t , which has on its rear end the shoulder x^1 , which catches the upper end of the vertical arm y' , pivoted at z' , and having the catch x^2 . As the movable frame descends, the catch x^2 unites with the catch l on the upper end of a rod rising from the weighted arm k . When the movable frame has completed the downward movement and begins to rise, it therefore lifts with it the weighted arm k . At the opposite extremity of this arm is the vertical rod a^2 , the top of which forms the plunger b^2 in the bottom of the die m . Thus, as the weighted arm is lifted by the rising of the traveling frame B , the plunger b^2 pushes up out of the die m the several lifts fastened together by the uniting-nail. When the plunger b^2 has been sufficiently raised to throw the united lifts out of the die m , the catch l strikes the stop o , by the inclined face of which it is released from the catch x^2 , and then the weighted arm k , with the plunger in the die m , drops so that the top of the plunger is even with the bottom of the die m . When the lever s is tipped back, the vertical arm y is drawn to one side by means of the spring u , so that it will not match with the catch rising from the weighted arm. The die m , as well as the pressure-block z , are removable, so that varieties of sizes may be employed. The delivering-arms q , where they are thrown back, as described, and out from under the pressure-block, move over an arm or guide, c^2 , by which the nail is carried to a recess at their extremity, in readiness for insertion into the lifts in the die, as before described.

The operations of my machine are as and in the order following: The leather, being placed upon the forming-die m , is cut into the requisite form by the descent of the traveling frame, moved by the eccentric, as before described. When the die is full of the cut lifts the awl is placed in position to perforate the same by the backward movement of the lever s , or the awl may be so placed as to perforate each lift as it is cut. When the die is filled with the lifts another forward motion of the lever s swings the delivering-arms into such position as to present a uniting-nail for insertion into the perforation of the lifts. The descent of the traveling frame to force in the nail brings the curved arm p' in contact with the standard o' , and thus allows the delivering-arms to fly back to their original position. After the nail is fully inserted, the traveling frame, as it rises, lifts the weighted arm, which, by means of the plunger, throws out the united lifts from the die. The weighted arm is then released and drops back to its original position. The table upon which the die m is placed is made adjustable, as is also the stop o .

What I claim as my invention, and desire to secure by Letters Patent, is—

1. The traveling frame B , having the pressure-block z , guides a , in combination with the

shaft *b*, gear *e*, gear *f*, shaft *c*, eccentric *d*, and rod *b'*, as described.

2. In combination with the traveling frame *B*, shaft *b*, shaft *c*, eccentric *d*, gears *e f*, the clutch *g*, lever *h*, rod *i*, and lever *j*, as described.

3. The combination, with the traveling frame *B*, operating as described, of the lever *s*, rod *v*, and awl *w*, as described.

4. The combination, with the traveling frame *B*, lever *s*, of the rod *e'* and spring-plunger *h'*, as and for the purposes described.

5. The combination, with the traveling frame *B*, of the lever *s*, slide *t*, spring *u*, arm *y'*, with its catch *l*, weighted arm *k*, plunger *n*, as described.

6. The stop *o*, to operate in combination with the weighted arm and catch *l*, as described.

7. The combination of the nail-receptacle *p*,

delivering-arms *q*, with the pressure-block *z* and die *m*, when operating in the manner described.

8. The combination of the catch *y*, curved arm *p'*, vertical rod *l'*, spring-stop *t'*, with its disk *u'*, with the stop *r*, the nail-receptacle, delivering-arms, and standard *o'*, as set forth.

9. In combination with the nail-box and delivering-arms, operating in the manner set forth, the rack *r'* and the arm *s'*.

In testimony that I claim the foregoing I have hereunto set my hand and seal this 13th day of December, 1873.
